FLUID COOLED SUPERHEATER
CONSTRUCTION

Charles S. Turner, Detroit, Mich.

Application May 2, 1931, Serial No. 534,490

7 Claims. (Cl. 122—481)

This invention relates to superheater constructions, and has for its object an improved organization of parts adapted especially for installation in locomotive boilers, though of equal utility in many stationary constructions. It has to do particularly with the protection of the superheater tube walls from impairment due to their exposure to the high heat conditions prevailing within the furnace chamber, and resultantly the confinement of the temperature of the steam within proper bounds. The invention herein disclosed centers particularly about those types of superheater installations which might be described as pendent or projecting, in that each of the several superheater tubes of an installation projects either vertically or horizontally into the heating space, being connected at one end with its manifold or header, while the outer or exposed end is closed; but each contains within it divisional walls or fluid conduits which selectively guide the course of both the steam flow and a column of cooling water within the shell-enclosed space, whose inlets and outlets are all at one end, and which may be compared cross-sectionally to a bay or elongated pocket, the entrance of which represents the connection with the superheater headers.

In the drawings:

Figure 1 is a sectional elevational view, showing many already-known parts of a water tube boiler installation, with one form of my improved superheater element here disclosed installed with relation thereto.

Figure 2 is a similar sectional elevational view of what might be termed the horizontal type of my superheater installation positioned within a locomotive or fire tubular type boiler.

Figure 3 is a partly sectional elevational view of a superheater header with depending tubes shown in relation to some such source of heat as a fire bed within a furnace; this being taken from a direction perpendicular to that of Figure 1, and designed to bring out particularly the plural and spaced relation of each end-closed superheater tube to its neighbors and to the adjacent boiler tube bank and furnace parts.

Figure 4 is a sectional elevational view of a single vertical superheater unit of the type herein dealt with, on a very much enlarged scale from the showing in Figure 1.

Figure 5 is a cross-sectional view on a larger scale of the preferred form of superheater tube unit shown in Figure 4, and as it is preferably employed for such vertical installations as are

illustrated in Figures 1 and 3, being taken along the line 5—5 of Figure 4.

Figure 6 is a longitudinal cross-sectional view on a larger scale of a preferred form of superheater tube employed in the horizontal installation suggested in Figure 2.

Figure 7 is a large scale sectional view of such a tube, similar to Figure 5, being taken along the line 7—7 of Figure 6.

Figure 8 is a sectional view taken substantially on the line 8—8 of Figure 6 and looking in the direction of the arrows, on a somewhat smaller scale and suggestive of a slightly modified form of connecting construction between the tube proper and the superheater manifold, wherein, by the use of a dividing diaphragm, the water-circulatory tubes of one side and the steam spaces about them are separated, forming a second or outflow series located in the other side or half of the shell shown.

Figure 9 is a sectional and elevational view of the end of one form of superheater tube, taken along the line 9—9 of Figure 4 and looking in the direction of the arrows there shown.

Referring first to what I have styled the vertical type of superheater element herein disclosed, the parts 12 in Figure 1 represent ordinary furnace walls and 13 the fuel bed or burning level. Across the upper portion of the furnace space extend the ordinary boiler tubes 14, which connect the drums 15 and 16 and which are in turn connected by means of the piping series 18 and 19 with the third drum 17. At 20 is shown a water supply pipe leading from a suitable water supply source such as the lower drum 15 and the outlet therefor is shown at 21, while at 22 is shown the valve and manifold controlling water supply to the pendent or vertically positioned superheater element 23 which forms the subject matter of one form of the invention here to be disclosed, ordinarily steam being admitted thereto through the inlet 24, and its egress therefrom taking place through its outlet or header 25. Most of the elements thus far mentioned are now well-known and in common use, and mention of them is made primarily for the purpose of enabling a clear understanding of the functioning of the superheater element 23 relatively thereto, the interior details and connections of one form thereof, brought out in Figures 4 and 5 particularly being now to be described.

The spaced relation of these several pendent superheater tubes 23 across the front of the boiler space is further illustrated in Figure 3, and it will be noted, both from an examination of that

figure and of Figure 1, that not only are their connection and header elements at their upper or inlet ends thermally protected by the baffle, as 12^a, from access of the furnace chamber heat, but that as well the presence of the ordinary boiler tubes 14, between some of which the upper portion of each superheater tube passes, affords an additional degree of protection against undue heating of their upper end connections, since the bank or boiler tubes in effect constitutes a more or less protective zone, though within the furnace chamber, which to a degree cuts down the amount of heat which would otherwise impinge upon, and make its way through, the wall 12^a. In the conventional form of furnace and boiler sheet shown, the oblique positioning of the wall or baffle 12^a enables the pendent superheater element 23 to project straight downwardly into the furnace as shown, the headers being arranged above the baffle. Since, however, the protection of the header from undue heat requires in any event that it be located outside the furnace chamber, if some other contouring of the walls thereof were used, it might be necessary to bend the length of each superheater tube, so that while generally depending into the furnace chamber, its header would be protected outside thereof, as for example at one side.

Each of the superheater tubes 23 is provided with a rounded or closed end, as 23^a, so that whatever steam or water is introduced into them can only emerge therefrom, after its circulatory phase has been completed, through the same end of the superheater assembly as that through which it entered, namely, the opposite end from the exposed pendent portion 23^a, and the guided circulation of both steam and water columns therewithin must be and is effected by the selective positioning within it of partitions or walls, in reality the various tubes or pipes which will be described, and which in the aggregate amount to a plurality of fluid-guiding longitudinal chambers, each of which is connected with either the steam system or the water system to the exclusion of the other, the steam inlet and outlet respectively being shown at 24 and 25 in Figure 1, while the valve-controlled water connections are indicated at 21 and 22 therein. It is obvious that the most exposed part of each superheater tube, namely its closed end 23^a, must have this water-cooling protection most of all, and to that end, in both of the forms herein disclosed, my invention centers about effecting the intimate relation of the water column with this end accordingly.

Figures 4 and 5, sectionally illustrative of this vertical or pendent type of superheater tube assembly should be studied in quite close association with Figures 1 and 3, particularly the former, since it must be borne in mind that the steam supply entering the space enclosed by the superheater tube 23 through the intermediate pipe 26, whose end is open, encounters at the far end of the superheater tube 23 the solid center of the spider 21, and finds its only possible egress to be through the annularly disposed spaces 28, between the pipe 26 and the peripherally surrounding cooling fluid pipes 29, whose outer peripheral points touch, indeed are preferably attached as by welding 30, to the inner surface of the end-closed tube or shell 23.

The water or other cooling fluid, on the other hand, entering past the inlet 22, proceeds through the relatively smaller central pipe 31 to the chamber 32 at the closed lower end of the superheater

tube 23, from which its only egress is upwardly through the several peripherally arranged passages 29 and out at the upper end through the part 21. The weight of the descending and relatively cool water column within the pipe 31 being greater than the thermally rising and more or less bubble-filled water passing upward through the passages 28 is generally sufficient to set up such a natural convection or self-induced circulation, quite aside from what pressure there may be in the cooling fluid supply system which is acting upon the water entering through the inlet 22, since the exposure of the outside welded wall lines 30 of each cooling pipe to the heat from the furnace chamber, through the walls of the outer tube 23, acts to rapidly raise their temperature.

Between these several inlet water pipes 29, however, are located the several spaces 28 to which heat units pass through the walls of the outer tube 23, for thermal action upon the steam within the spaces or chambers 28 and upon the outflowing columns of fluid to be acted upon.

Most of the operative principles involved in the construction and use of the vertical or pendent type of superheater tube thus far discussed carry over into the horizontal or so-called locomotive type, illustrated particularly in Figures 2, 6, 7, and 8, in that the requirements for the adequate protection of the header connections from undue heat remain, together with the general requirement that the outer or heat-exposed end of the superheater tube be closed, and that ingress and egress both of steam and of the cooling medium be at the header end of the tube. As brought out in Figure 2, the horizontal tube 40 is connected, as at 41, with a steam source, the flow from which proceeds through the tube 42 spacedly lengthwise of the exposed or superheater tube 40. The outer end of this tube 42 is spaced from the closed or pocketed end of the tube 40, so that the steam emerges therefrom into the chamber 43. Arranged in spaced relation about the steam tube 42 are a series of water-cooling tubes, of which six are shown cross-sectionally in Figures 7 and 8. These extend lengthwise of the tube and are arranged in two series, three of these tubes, as a, b, c, being designed for the outward flow, that is toward the outer end of the superheater tube, of the cooling water which enters through the inlet 44, while the remaining three, as d, e, and f, form U-shaped continuations of the respective tubes a, b, c, being positioned on the other side of the diametrical diaphragm 45, are designed to care for the return flow of the cooling medium toward the water outlet 46. These pipes are preferably welded along their lines of union to the inner surface of the superheater tube wall 40, as indicated at 48, but they are in spaced relation thereabout, leaving alternated spaces, as 47, through which the steam introduced lengthwise of the tube 40 through the tube 42 and thence discharged in the chamber 43 may make its way backward toward the steam outlet 49. Thus a continuous cooling fluid current is maintained through the passages thus peripherally disposed within the shell 40 and about the outside of the steam pipe 42, while on its return travel the steam as it passes through the several vacant spaces 47 is exposed to the maximum of superheating influence which makes its way through those wall portions of the superheater tube 40 which bound the outside of the several spaces 47.

It will be noted that the three water inlet channels, a, b, and c, are located on the under

- side of the superheater unit as positioned in the furnace space, whereas the three outlet tubes *d*, *e*, and *f* are located in the top side, thus giving the cooling fluid stream the benefit of whatever acceleration may result from the outgoing and more or less bubble-filled cooling water having a tendency to rise from the level of the three lower cooling tubes *a*, *b*, and *c* to that of the three upper tubes *d*, *e*, and *f*. Of course any desired number of cooling tubes, more or less than those herein illustrated, could be employed, depending upon the operative conditions to be dealt with. As brought out by comparison of the cross-sectional Figures 6 and 8, the steam entering the centrally located steam inlet pipe 42, from the steam source connection 41, passes through the apertured diaphragm 45 which separates the inlet series of water-cooling tubes, *a*, *b*, and *c* from the outlet series *d*, *e*, and *f*, so that the water flowage pipes are kept wholly to themselves, leaving all of the interspersed steam outlet spaces 47 clear for the steam outflow after it has been delivered into the chamber 43 through the inlet pipe 42.
- The two forms of end-closed superheater tube illustrated herein and which throughout this specification I have referred to as the "vertical" and the "horizontal" types respectively are mutually interchangeable provided forced circulation of the cooling fluid column can be relied upon; but if the variances in temperature between the relatively cool inflowing column and the rapidly rising-temperated outflow column be relied upon alone for starting this cooling fluid circulation, my experience has been that while the so-called "horizontal" type can, even under these conditions, be substituted for the "vertical" type, the reverse is not true, that is to say, the so-called "vertical" type could not be substituted for the "horizontal" type.
- What I claim is:
1. A fluid-cooled superheater tube unit, having, in combination with an outer shell adapted for inlet and outlet connection at the same end with an external steam supply source, the other end of said shell being closed, cooling fluid conducting pipes arranged within said outer shell in position to conductively receive heat units imparted to certain external surface portions thereof from an outside source and adapted in turn to modifyingly transmit the normally lower temperature of their contents to certain of the spaces within said outer shell not occupied by such pipes, and an interiorly positioned steam pipe for introducing a supply of steam adjacent the closed end of said outer shell, whence it is adapted to emerge, while subjected to the thermal influences described, through the available lengthwise passages therein.
  2. In a superheater construction, in combination with a common header, a plurality of fluid-cooled superheater tube units terminally connected therewith in spaced relation to one another, each of said units comprising an outer shell closed at its end remote from its point of connection with the header, an interior tube spacedly surrounded by said outer shell, and a plurality of fluid-conducting tubes located within said outer shell and surroundingly of said interior tube, each of said elements being separately connected at its inner end with external fluid supply and outlet elements, whereby the fluid columns admitted to the contents of the several fluid-conducting passages are subjected to heat-interchanging influence with the contents of those adjacent, thereby regulatably holding within predetermined limits the heating influence exerted upon the outer shell of the several superheater tubes.
  3. A fluid-cooled superheater tube unit, comprising a pair of coaxially disposed tubes arranged one within the other in spaced relation, the outer end of the larger one of said tubes being closed, means for conducting steam through the inner to a point adjacent the closed end of the outer tube and for returning the same through said outer tube, and a series of fluid-cooling outflow and return tubes positioned between the spaced walls of said coaxially disposed tubes for modifyingly influencing the temperature thereof and of steam therewithin, a cooling fluid supply source connected to the outflow and take off means which are in turn connected to the return tubes.
  4. In a fluid cooled superheater, a conduit, a casing longitudinally surrounding the conduit and radially spaced therefrom to form a chamber, and a plurality of cooling fluid ducts circumferentially spaced within said chamber to form, with said casing and conduit, a plurality of passages.
  5. A superheater unit comprising a casing, a plurality of tubes within said casing, at least one of said tubes being connected to a steam inlet, others of said tubes being connected to a fluid cooling system and forming a cooling fluid circulating system spaced circumferentially of said inlet, and means integrally connecting the tubes of said circulating system to the casing.
  6. In a heater unit, in combination, a pair of substantially concentric spaced pipes forming an annular chamber therebetween, a plurality of independently walled conduits extending longitudinally within said chamber and having wall portions abutting said pipes, said conduits being circumferentially spaced from each other around said chamber and forming a plurality of spaced independent passageways between said conduits and within said chamber, whereby fluid may be conducted through said annular chamber both inside and outside of said conduits, integral heat bridging means between said conduits and at least one of said pipes, an inner one of said concentric pipes being connected to certain only of the channels formed by said conduits and the passageways therebetween, and separate fluid supply means connected one to said inner pipe and passageways and another to said conduits.
  7. In a heater unit, in combination, a pair of substantially concentric spaced pipes forming an annular chamber therebetween, a plurality of independently walled conduits extending longitudinally within said chamber and having wall portions abutting said pipes, said conduits being circumferentially spaced from each other around said chamber and forming a plurality of spaced independent passageways between said conduits and within said chamber, whereby fluid may be conducted through said annular chamber both inside and outside said conduits, integral heat bridging means between said conduits and the outer of said pipes, a cooling flowage system having inflow and outflow connections connected to said conduits at the same end of the unit, and another cooling fluid system having inflow and outflow connections at the same end of the unit connected to one of said concentric pipes and to the passageways formed by the spaces between said conduits.
